UNITED STATES PATENT OFFICE.

CHARLES A. LUNDY, OF RENO, NEVADA, ASSIGNOR TO LUNDY GAS ENGINE COMPANY, OF RENO, NEVADA, A CORPORATION.

GAS-ENGINE.

1,210,088.

Specification of Letters Patent. Patented Dec. 26, 1916.

Application filed October 25, 1915. Serial No. 57,710.

To all whom it may concern:

Be it known that I, CHARLES A. LUNDY, a citizen of the United States, residing at Reno, in the county of Washoe and State of Nevada, have invented certain new and useful Improvements in Gas-Engines, of which the following is a specification.

My invention relates to that class of gas-engines in which a single ported cylinder 10 is arranged for rotation on its axis, and by reason of such rotation is adapted to carry its port, in timely succession, into registry with fixed charging, exploding and exhausting connections; and more particularly my 15 present invention relates to and concerns that gas-engine of this type which was patented by me March 31, 1914, No. 1,091,854, and the improvements thereon for which I have now pending an application Serial No. 20 842,622, filed June 3, 1914. In the development of this engine certain features have attained a prominence which has arisen from the necessities of good practice. These may be briefly and generally mentioned as relating to the shape of the cylinder; the means for revolubly mounting and locking the cylinder in its seat to resist end thrust, while adapting it for rotation on its axis; and the means for efficiently adapting the fixed 25 plural-ported sleeve-valve and associated valve-chamber or head to the rotating cylinder.

In these features and improvements, my present invention consists and for a full understanding thereof I shall now describe them in detail in connection with the accompanying drawings, in which—

Figure 1 is an elevation of my gas-engine. Fig. 2 is a plan of the same, broken in part. 40 Fig. 3 is an enlarged view, partly in elevation and partly in section, showing one cylinder complete and a portion of another cylinder. Fig. 4 is a horizontal cross-section through the valve-area of the cylinder, taken on the line $x-x$ of Fig. 5. Fig. 5 is a vertical cross section of the same on the line $y-y$ of Fig. 4. Fig. 6 is a section in the line $z-z$ of Fig. 3, showing the locking and adjusting means of the revoluble cylinder bearing. Fig. 7 is an elevation of the packing-sleeves of the valve-area.

1 is the crank case, which is also the bed of the engine.

2 are the cylinders. I have here shown a

four cylinder engine, though it will be understood that the engine may have one or any number of cylinders. Each cylinder is revolubly locked to the bed by a connection which will enable it to resist end-thrust, due to explosion, and will adapt it for rotation on its axis. This connection is shown in Fig. 3, and is as follows. As all the cylinders are alike, a description in the singular number will be simplest. Extending from the crank-case is an annular shell or housing 3 which forms the seat for the cylinder. This housing is open at both ends, and has formed on its inner surface, near its upper or outer end, an inwardly extending rib or lug 4, which as shown in Fig. 6, is in two spaced opposite sections. Closely fitted upon the exterior of the lower portion of the cylinder is a spiral gear 5. The fitting is by means of threads 6 on the cylinder, the gear being threaded on its inner diameter down to a shoulder 7, and said gear is screwed up on the threads 6 of the cylinder to this shoulder, as seen in Fig. 3. The portion of the gear above the shoulder is formed as a thrust bearing race 8 for the ball bearings 9.

10 is a lock-ring which on account of its lower flange 10' spaced in sections, as seen in Fig. 6, clamps in place by a partial turn on or under the rib or lug 4 on the inner surface of the cylinder-seat housing 3.

11 is an adjusting-ring threaded into the lock-ring 10, and formed on its lower surface with the complemental race 12 for the ball bearings 9. The inner surface of the adjusting-ring 11 is hollowed out for a packing space 13.

The seat housing 3 has at its lower or inner end a flange 14 upon which rests a suitable lower anti-friction bearing which in its best form comprises the inner ring 15 freely fitted around the cylinder, and supporting the spiral gear 5, the outer ring 16 resting on the flange 14 and having an inclined inner surface, and the taper rolls 17 between the two rings. The annular seat housing 3 may be cast with the crank case, or it may be a separate part bolted thereto.

The gear 5 is screwed on the cylinder in the direction that power is applied to rotate the cylinder, and it locks in place against the shoulders at 7, thus needing no keys, set screws, or the like to hold it. The finished surface of the gear fits closely to the finished

surface of the cylinder and thus insures a perfect alignment. A special feature to be noted in this revoluble lock connection for the cylinder is that the locking and adjusting nut member is doubled, and comprises the outer lock-ring 10, and the inner adjusting-ring 11. The outer ring 10 needs only a partial turn to lock it to or to release it from the housing rib or lug 4, and the inner ring 11 threads into the outer ring and rests on the ball bearing 9. This construction provides for an adjustment of the bearings that is not disturbed by the removal of the cylinder from the seat-housing 3.

The cylinder 2 has a peculiar and novel form or shape, in that its upper portion is a relatively long slender neck 2' which forms a valve. This valve neck extends directly and centrally from the main body or piston-area of the cylinder, and is open at both ends. It forms not only the valve member of the valve area or system but also the compressing and firing chamber directly over the center of the piston. It has the advantages of simplicity and economy and it has power developing properties as will be more fully seen as the description herein progresses. This neck 2' is of such length and diameter in proportion to a given size cylinder, as to form the correct size compressing and firing chamber. In the wall of the neck 2' of the cylinder is made the single port 18.

Around the lower portion of the neck 2' in grooves therein are seated the packing rings 19 in any suitable number, say four, for example. Upon the top of the neck is screwed down the annular lock-nut 20, in a groove in the face of which is seated a packing ring 21. The port 18 in the cylinder neck lies in the area between the uppermost packing ring 19 and the lower surface of the nut 20, and around this area is fitted a set or series of packing-sleeves 22. These sleeves may be in any desired number: I have, for illustration, shown two. They are nested, one within the other and interfit closely. An essential feature of these sleeves to be particularly noted is that each is not only severed longitudinally, but the severed edges are separated by a distinct space to provide for a continuance of fit under all conditions of expansion and contraction. These spaces are designated by 23, and they are best arranged in the two sleeves opposite each other, as seen in Fig. 4. These sleeves while they interfit closely do not normally closely fit the neck of the cylinder, that is to say, the inner sleeve loosely fits the neck being separated from the exterior surface of said neck by a distinct space, as shown in Figs. 4 and 5, at 24. The sleeves contract inwardly when heated and expanding, thus lessening their diameter on the inside and

retaining the same closeness to the member on the outside, thus preventing a loss of gas, and avoiding binding and cutting.

The sleeves 22 fit between the shoulders formed by the uppermost packing ring 19 and the lower surface of the lock nut 20, as best seen in Fig. 5, and they are locked or pinned to the neck, as, for example, at 22', Figs. 4 and 5, so that they rotate therewith. Through the walls of the sleeves is made a port 25 which permanently registers with the port 18 of the cylinder neck, as shown in Fig. 4.

27 is a fixed valve-seat sleeve. It is a cylindrical shell closed at the top except for a spark-plug hole 28 threaded in the center thereof, as in Fig. 5. It has the inlet port 29 cut in one side and the exhaust port 30 cut in the other side. It slips down over the cylinder valve neck 2', fitting firmly against the face of the packing ring 21 in the nut 20, the faces of the lower set of packing rings 19, and the outer surface or face of the outermost packing sleeve 22, as shown in Fig. 5, thus preventing the passing of any air or gas mixture by the valve or packing rings or sleeves.

The valve-seat sleeve 27 is held fixed and non-rotatable by the cylinder head or valve chamber 31 which fits over it. This head 31 has a top flange 32 overlapping upon the upper end of the sleeve valve 27 and lock pins 33 through this flange into the sleeve connect the two. A packing lock nut 34 is fitted to the lower ends of the sleeve and head. The head 31 has an intake passage 35 which registers with the inlet port 29 of the sleeve 27, and an exhaust port 36 which registers with the exhaust port 30 of the sleeve. It will now be seen that as the aligned ports 18 and 25 of the cylinder valve-neck and its packing sleeves rotate they will alternately open and close the aligned inlet and exhaust ports and passages of the fixed valve-seat sleeve and head. All these ports are laid in proper width and separated to provide the correct timing of a four cycle motor. To properly support and hold the valve-chamber head 31 stationary, said head has extended lugs 37 from which tie-rods or bolts 38 pass down to lugs 39 on the cylinder-seat-housing 3 of the crank-case, as seen in Fig. 1. In case the seat-housing 3 be made as a separate piece from the crank-case, it may be made with other lugs 40 for bolting it to the casing, as seen in Fig. 3.

The driving mechanism for rotating the cylinders is as follows: The seat-housing 3 has made in its face an opening 41, surrounded by a flange 42, to which the cap 43 bolts and holds the bearings 44 and the driving shaft 45 in place, and allowing the spiral pinion 46 to engage the spiral gear 5 through the opening 41. The shaft 45 may be driven by any suitable connections, as,

- for example, by the silent chain 47 from the crank shaft 48. The spiral gears 46 and 5 are of such ratio that the cylinder 2 must revolve at one half the speed of the crank 5 shaft 48. To the crank shaft are connected the piston rods, one of which is shown by 49 in Fig. 3, and these at their other ends are connected to pistons which are not shown herein, it being sufficient for the purposes of 10 5 to the present application to state that these pistons are so constructed as to permit the cylinders to rotate around them with the least possible friction, as I have fully disclosed in my patent hereinbefore referred to.
- 15 In the present drawings I have shown means for air-cooling which may now be described; but as the novelty of these means form the subject matter of a divisional application no claims therefor are made herein.
- 20 The cylinder 2 above its revoluble connection with the seat-housing 3, and below its valve neck 2', that is, in its piston-area, is provided with fins or flanges 50, helically directed and so pitched or inclined as to 25 serve as fan blades to pull the air away from the neck 2' and its assembled parts, as the cylinder revolves. These fins or flanges are in practice best cast with the cylinder. The stationary valve-chamber head 31 is surrounded by a series of cooling fins or flanges 51, the upper one of which is finished with the lugs 37 for the tie rods 38 heretofore mentioned.
- Surrounding the whole engine is an air 35 directing shell or housing 52. At the front end this housing is only partly open, as at 53, being closed by the wall 54 in the remaining part. At the rear end the arrangement is relatively the opposite of that at the 40 front end, said rear end being open in part at 55 and closed in part by a wall 56, the openings in front and rear being thus on opposite sides of a central longitudinal vertical plane through the housing. The current of 45 air, therefore, which enters through the opening 53 at the front end is on one side of the cylinders, which revolving into said current catch the air and pass it to the other side in line for it to pass out through the 50 opening 55 at the rear end of the housing. The current is drawn out by the suction fly wheel 57 connected with the housing 52 by a housing 57'. The course of the air is indicated by the arrow in Fig. 2. The cylinders 55 are timed to make one complete revolution between each explosion, thus bringing every part into the same temperature of cooling air once after each heating, causing a uniform expansion of the cylinder everywhere 60 and a uniform cooling of all working parts. 58 indicates the magneto, and 59 the magneto gear housing. 60, in Fig. 1, is the oil tank, and 61 is the exhaust manifold.
- I claim:—
- 65 1. In a gas-engine having a cylinder
- adapted for rotation on its axis, and means called into timely action by the rotation of the cylinder for admitting an explosive mixture, exploding said mixture and exhausting the products of explosive combustion, the 70 means for revolubly mounting said cylinder comprising a fixed housing in which the cylinder is seated, said housing having an internal lug in its upper portion, a gear fitted upon the end of the cylinder within the housing, said gear having a ball race in its top, a lock-ring detachably engaging under the lug of the housing, an adjusting ring screwed into the lock-ring around the cylinder, said adjusting ring having a complementary ball 75 race in its under surface, balls between the two surfaces, and an anti-friction bearing carried in the base of the housing and supporting the gear of the cylinder.
2. In a gas-engine having a cylinder 80 adapted for rotation on its axis, and means called into timely action by the rotation of the cylinder for admitting an explosive mixture, exploding said mixture and exhausting the products of explosive combustion, the 85 means for revolubly mounting said cylinder comprising a fixed housing in which the cylinder is seated, said housing having an internal lug in its upper portion, a gear fitted upon the end of the cylinder within the 90 housing, said gear having a ball race in its top, a lock-ring detachably engaging under the lug of the housing, an adjusting ring screwed into the lock-ring around the cylinder, said adjusting ring having a complementary ball race in its under surface, balls between the two surfaces, and an anti-friction bearing carried in the base of the housing and supporting the gear of the cylinder.
3. In a gas engine, the combination of a cylinder having a centrally extending reduced neck portion forming the charging, compression and firing chamber and the controlling valve therefor, said neck portion having in its wall a single port; a non-rotating valve-seat sleeve fitted over said cylinder valve neck and having a spark plug hole in its top and separate ports in its sides with which the port in the cylinder valve neck successively registers as the cylinder rotates; suitable packing between the valve neck and seat-sleeve; a non-rotating head fitted over said seat sleeve and having inlet 100 and exhaust passages communicating with the ports of said seat-sleeve; means for revolubly mounting said cylinder to adapt it for rotation on its axis; and means driven by the engine for effecting the timely rotation of the cylinder.
4. In a gas-engine, the combination of a cylinder having a centrally extending reduced neck portion forming the charging, compression and firing chamber and the 105

- controlling valve therefor, said neck portion having in its wall a single port; a series of packing rings seated about the lower portion of said valve neck, and a lock nut 5 carrying a packing ring, screwed upon the upper end of the valve neck; a nest of concentric closely interfitting expansible packing sleeves freely embracing and secured to the valve neck between the packing rings 10 and lock nut, said sleeves having a port alined with the port of said valve neck; a non-rotating valve seat sleeve fitted over the packing rings and packing sleeves, and having a spark-plug hole in its top and separate ports in its sides with which the ports 15 in the cylinder valve neck and packing sleeves successively register as the cylinder rotates; a non-rotating head fitted over said valve-seat sleeve and having inlet and exhaust passages communicating with the ports of said seat-sleeve; means for revolvably mounting said cylinder to adapt it for rotation on its axis; and means driven by the engine for effecting the timely rotation 20 of the cylinder.
5. In a gas-engine, the combination of a cylinder having a centrally extending reduced neck portion forming the charging, compression and firing chamber and the controlling valve therefor, said neck portion having in its wall a single port; a series of packing rings seated about the lower portion of said valve neck, and a lock nut 30 carrying a packing ring, screwed upon the upper end of the valve neck; a nest of concentric closely interfitting expansible packing sleeves freely embracing and secured to the valve neck between the packing rings and lock nut, said sleeves having a port 35 alined with the port of said valve neck, and each of said sleeves being severed longitudinally with its severed edges spaced apart and the inner sleeve spaced from the valve neck; a non-rotating valve-seat sleeve fitted over 40 the packing rings and packing sleeves, and having a spark-plug hole in its top and separate ports in its sides with which the ports in the cylinder valve neck and packing sleeves successively register as the cylinder rotates; a non-rotating head fitted over 45 said valve-seat sleeve and having inlet and exhaust passages communicating with the ports of said seat-sleeve; means for revolvably mounting said cylinder to adapt it for rotation on its axis; and means driven by the engine for effecting the timely rotation 50 of the cylinder.
6. In a gas-engine, the combination of a cylinder mounted for rotation on its axis, 55 said cylinder having a single port; a non-rotating valve-seat sleeve fitted to said cylinder and having a spark plug hole in its top and separate ports in its sides with which the ports in the cylinder valve neck and packing sleeves successively register as the cylinder rotates; a nest of concentric closely interfitting packing sleeves between the cylinder and seat-sleeve, said packing sleeves being secured to the cylinder and having a port alined with the port of the cylinder, and each of said sleeves being severed longitudinally with its severed edges spaced apart and the inner sleeve spaced from the cylinder; and a non-rotating head fitted over the valve-seat sleeve and having inlet and exhaust passages communicating with the ports of said seat-sleeve.
7. In a gas-engine, the combination of a cylinder mounted for rotation on its axis, said cylinder having a single port in its side; a non-rotating valve-seat sleeve fitted to the cylinder and having in its top a spark plug hole and in its sides opposing inlet and exhaust ports with which the port of the cylinder is adapted by the rotation of said cylinder to successively register; a packing ring between the cylinder and the lower portion of the valve-seat sleeve; a packing ring between the cylinder and the upper portion of the valve-seat sleeve; a nest of concentric closely interfitting packing sleeves secured to the cylinder and lying between it and the valve-seat sleeve in the area between the packing rings, said packing sleeves having ports alined with the cylinder port and each of said packing sleeves being severed longitudinally and its severed edges spaced apart, and the innermost of said sleeves being spaced from the cylinder; and a non-rotating head fitted over the valve-seat sleeve and having passages alined with the ports thereof.
8. In a gas-engine, the combination of a ported cylinder member; a ported valve-seat member fitted to said cylinder; means for effecting the rotation of one of said members relatively to the other for successively registering their ports; suitable inlet and exhaust connections; and a nest of concentric closely interfitting ported packing sleeves between the cylinder and valve seat-members, said sleeves being secured to one of said members and each of said sleeves being severed longitudinally with its severed edges spaced apart and the inner sleeve spaced from the cylinder member.

In testimony whereof I have signed my name to this specification in the presence of two subscribing witnesses.

CHARLES A. LUNDY.
